United States Patent Office.

WILLIAM SINCLAIR THOMPSON, OF ROCHESTER, NEW YORK.

Letters Patent No. 101,944, dated April 12, 1870.

IMPROVEMENT IN FRUIT-JARS.

The Schedule referred to in these Letters Patent and making part of the same

To all whom it may concern:

Be it known that I, WILLIAM SINCLAIR THOMPSON, of the city of Rochester, county of Monroe and State of New York, have invented a certain new and useful Improvement in Fruit-Jars, of which the following is a specification.

Nature of Invention.

This invention consists of a clamp and spring of peculiar construction for holding down the cover, at the same time giving it a degree of elasticity, as hereinafter described.

General Description.

In the drawings—

Figure 1 is a vertical section, and

Figure 2, a perspective view of the clamp and spring detached.

Figure 3, a cross-section of the clamp.

A is the jar, and

B, the cover, pressing upon the packing-ring *a*, in the usual manner.

C is the clamp, which is preferably made with projecting flanges *b b*, forming by this means a depressed cavity or groove, *e*.

Its claws *ff* hold under the beads *g g* of the jar in the ordinary way, and in its top are made, at suitable distances apart, two longitudinal slots *h h*, with inner end enlargements or cross-slots *i i*, as clearly shown.

D is the spring, which is preferably cut or formed from a piece of flat steel band, of a width sufficient to fit easily in the cavity or groove *e* of the clamp. Its ends are cut with narrow shanks *k k*, corresponding in width with the slots *h h*, and its extremities with heads or lugs *l l*, corresponding with *i i*.

This spring is compressed or bent up, so that the heads *l* will enter holes *i* on the under side of the clamp, and is then released, the natural expansion causing the ends to spread, so as to rest in the slots *h*, as in fig. 2, thereby preventing detachment.

In this condition the clamp and spring are applied

to the jar over the cover, thereby holding the latter down to the packing.

I am aware that a coiled spring has been combined with a cover and clamp, the whole forming one connected fixture, and the cover having a stem passing up through the clamp, by which the spring is compressed by the action of the finger.

I expressly disclaim the broad principle involved, and confine myself to my method of application.

The advantages of my arrangement are that I get a better bearing upon the cover. The cover is disconnected from the clamp and spring, so that if desired, when the atmospheric pressure has fixed the cover in place, the clamp and spring may be removed.

My device is much simpler and more easily made and applied, and the construction and arrangement are totally different.

Finally, the sunken cavity or groove of the clamp allows the spring to sink in out of sight, so that a casual examination would only show the bearings of the clamp itself upon the cover, while at the same time said cavity serves as a guide to keep the spring in place and to thus produce a uniform pressure upon the cover.

Claim.

What I claim is—

1. The combination of the clamp C and flat spring D, united through the medium of the slots *h i* and bearings *k l*, in the manner and for the purpose specified.

2. The clamp, provided with the guards *b*, forming a cavity, *e*, for the purpose of supporting the spring and preventing a lateral movement of the same, substantially as set forth.

In witness whereof I have hereunto signed my name in the presence of two subscribing witnesses.

WILLIAM SINCLAIR THOMPSON.
